UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO.

RAILWAY-TIE PLATE.

SPECIFICATION forming part of Letters Patent No. 672,719, dated April 23, 1901.

Application filed July 25, 1900. Serial No. 24,778. (No model.)

To all whom it may concern:

Be it known that I, JOHN W. STEPHENSON, of Toledo, in the county of Lucas and State of Ohio, have invented a new and useful Improvement in Railway-Tie Plates, of which the following is a full, clear, and exact description, reference being had to the accompanying drawings, forming part of this specification, in which—

10 Figure 1 shows in end elevation, partly in section, a tie-plate constructed in accordance with my invention. Fig. 2 is a top plan view of the plate. Fig. 3 is a bottom plan view, and Fig. 4 is a vertical cross-section on the line IV IV of Fig. 3. Fig. 5 is a bottom plan view of the tie-plate, showing in dotted lines a tie-rod applied thereto. Fig. 6 is a vertical cross-section on the line VI VI of Fig. 5.

In the drawings, 2 represents the tie-plate, 20 having on its surface shoulders 3 4, between which the rail *a* is set, and having holes 5 5 for spikes by which the plate is secured to the tie. On the under side of the plate are ribs 6 6, which extend in a direction transverse to 25 the rail, so as to be parallel with the grain of the wood of the tie. These ribs are preferably somewhat sharp, so that they may be forced into the tie, and are of greater depth than width, and the spike-holes 5 are formed in 30 line with the ribs, preferably immediately at the ends thereof. This is important, because the ends of the ribs constitute abutments against which the spikes bear. They thus brace the spikes and cause them to hold with 35 greater stability, and by reason of the extended bearing which they afford they prevent the wear of the margin of the hole, which is apt to occur by reason of the vibration of the plate in contact with the spike. It is important also for the further reason that being 40 in line with the ribs the spikes enter and close the ends of the splits in the wood which are formed by the ribs. These splits are very objectionable, because they open the grain of

the wood to receive water, which lodges there-in and sets up decay. My invention affords means by which this evil may be minimized. The splits at the ends of the ribs remote from the spike-holes are not closed by the spikes; but the disadvantage of the splits at these 50 points is lessened by terminating the ribs short of the end of the tie-plate, so as to afford an overlapping margin *b b* of the plate, which covers the splits and protects them from water. 55

In Figs. 5 and 6 I show a device which enables the tie-plate to be fitted with a tie-rod connecting it with the plate at the other side of the track. This device consists of a socket or recess *c* on the under side of the plate in 60 which a spike-hole *d* is formed. The tie-rod is placed in this socket and is held therein and fixed to the plate and to the tie by one of the spikes. This device is claimed in another patent application filed by me on July 25, 65 1900, Serial No. 24,779.

Within the scope of my invention as defined in the claims changes may be made by those skilled in the art, since

What I claim is—

1. A tie-plate having on its under side a rib which extends transversely to the position of the rail, and a spike-hole, said rib being in line with the spike-hole and terminating immediately at the hole and constituting an 75 abutment for the spike; substantially as described.

2. A tie-plate having on its under side a rib which extends transversely to the position of the rail, and is of greater depth than width, 80 and a spike-hole formed in line with the rib; substantially as described.

In testimony whereof I have hereunto set my hand.

JOHN W. STEPHENSON.
